UNITED STATES PATENT OFFICE.

EDWARD FINK, OF MILWAUKEE, WISCONSIN, ASSIGNOR OF ONE-HALF TO HALLECK W. SEAMAN, OF CLINTON, IOWA.

RETORT APPARATUS.

1,213,347.

Specification of Letters Patent. Patented Jan. 23, 1917.

Application filed June 10, 1915. Serial No. 33,236.

To all whom it may concern:

Be it known that I, EDWARD FINK, a citizen of the United States, residing at Milwaukee, in the county of Milwaukee and State of Wisconsin, have invented certain new and useful Improvements in Retort Apparatus, of which the following is a specification, reference being had to the accompanying drawing, forming a part 10 thereof.

This invention relates to retort apparatus, and the objects of the invention are to provide suitable retort apparatus for the continuous reduction of zinc oxid, for example.

One of the objects of the invention is to provide retort apparatus by the use of which the reduction of zinc oxid, for example, may be conducted as a continuous operation, and the condensation of the zinc vapor is continuous, while the feeding of the material to be treated in the retort may be either continuous or intermittent, and the discharge of waste solid materials from the retort may be either continuous or intermittent.

A further object of the invention is to provide retort apparatus of such a character that it is not necessary at any time to disconnect the condenser from a retort either for the purpose of charging the retort, or for the purpose of removing spent material from the retort. The feeding of the material to retorts and the discharge of spent material from the retorts may be accomplished by mechanical means and thereby effect a great saving in time and labor as compared with the known forms of zinc retorts.

In general terms the invention comprises an upright retort provided with an outlet to a condenser, and preheating and feeding apparatus for the retort so located with respect to the outlet to the condenser that the outlet cannot be choked or blocked by material fed to the retort, and the lower end of the retort is provided with mechanism whereby the spent material in the retort seals the interior of the retort from the atmosphere while at the same time a part of the spent material may be readily removed without disturbing the operation of the retort or admitting air to the retort. Preferably a plurality of retorts, sufficient in number to accommodate the requirements of the plant where they are operated, are grouped together in a single furnace or combustion chamber.

Referring to the drawings which accompany this specification and form a part hereof, which drawings illustrate embodiments of this invention and on which drawings the same reference characters are used to designate the same parts wherever they may appear in each of the several views, Figure 1 is a longitudinal vertical section through a furnace, one of the retorts and associated parts therein being shown in section, and other parts being shown as broken away to clearly illustrate the constructions; Fig. 2 is a transverse vertical section of the furnace, one of the retorts therein and associated parts being shown in section, and the other retort 60 being shown with parts broken away; Fig. 3 is a partial vertical longitudinal section of a furnace, one of the retorts and associated parts therein being shown in section, and another of the retorts and associated parts 65 being shown as broken away, and illustrates a modified form of retort apparatus; Fig. 4 is a transverse vertical section of the furnace illustrated by Fig. 3, one of the retorts and associated parts therein being shown in 70 section and the other retort and associated parts therein being shown with parts broken away; and Fig. 5 is a plan view of one of the retorts illustrated by Figs. 3 and 4.

Referring to Figs. 1 and 2 of the drawings, the reference numeral 1 designates a furnace which may be constructed in any suitable or convenient manner for the purpose desired, the particular furnace illustrated being provided with burner nozzles 85 2 and 3 for liquid, gaseous or pulverized fuel and stacks 4 and 5 being provided for the escape of the products of combustion. A supporting frame 6 is placed in the lower part of the furnace 1, and upon this frame 90 are supported base members 7, which are preferably provided with ledges 8 to support retorts 9. The retorts 9 may have substantially perpendicular walls, or the walls may flare outwardly so that the lower parts 95 of the retorts are larger than the upper parts, to facilitate the descent of material therein, but it is preferred to make the base members 7 considerably larger at their bottoms 100 than at their tops, so that the material therein can readily move downwardly as the material is removed from below.

A partition 10, of suitable refractory material, separates the combustion chamber 11 from the chamber 12 in which the base mem- 110

bers 7 are located, so as to prevent the base members from being heated to any considerable extent. The lower ends of the base members 7 are partly closed by the revoluble cones 13, which are supported upon shafts 14, and which may be revolved either continuously or intermittently by means of suitable mechanism, as for example, the gears and shafts illustrated by Fig. 2 of the drawings. The tops of the revoluble cones 13 may be smooth or corrugated, or provided with upstanding ribs 15, as illustrated by Figs. 1 and 2 of the drawings, and each shaft 14 may be provided with an agitator 16, having an arm disposed at an angle like a screw or propeller blade to force the material down as the agitator is revolved. Conveyors 17 of any suitable construction, may extend into the chamber 12 and under the base members 7, to receive the material discharged from the base members 7 and remove it to the exterior of the furnace.

Each retort is provided with an outlet 18 which communicates with a condenser 19, and a preheating and feeding tube 20 communicates with the interior of each retort and is so disposed with respect to the outlet 18 that material fed into a retort by the feeding tube cannot reach the outlet 18, thereby providing a pocket adjacent the outlet 18. The feeding tubes 20 are illustrated as provided with hoppers 21 at their upper ends and the material to be fed to the retorts can be supplied to these hoppers either by hand or by suitable conveying mechanism.

The top of the furnace is provided with removable closures 22, of sufficient size to enable the removal of a broken or damaged retort and the insertion of a new retort therefor.

Referring now to Figs. 3, 4 and 5 of the drawings, the furnace 23 is provided with a partition 24, corresponding to the partition 10 already described, and for the same purpose. A second partition 25, is provided above the retorts, forming, with the roof of the furnace, a chamber 26 through which the preheating and feeding tubes 27 extend, and the products of combustion from the combustion chamber 28 can be diverted to a greater or less extent from passing directly to the stacks 29 and 30 by means of the dampers 31 and 32 and compelled to pass through the apertures 33 and 34 in the partition 25 and around the preheating and feeding tubes 27 to the flue exits 35 and 36, located above the partition 25. The hot products of combustion passing around the feeding tubes 27 heat the material contained therein and drive the moisture therefrom and preheat the same before the material enters the retorts.

The retorts 37 in the furnace illustrated by Figs. 3 and 4 of the drawings, are ellipti-

cal in shape, with their long diameters placed longitudinally of the furnace and they are supported upon flaring base members 38 and are provided with outlets 39 which communicate with condensers 40 in 70 the same general manner as the retorts already described and illustrated by Figs. 1 and 2 of the drawings.

The feeding tubes 20 illustrated by Figs. 1 and 2 of the drawings are illustrated as 75 extending down into the interiors of the retorts below the outlets 18, so that the material cannot accumulate in or opposite the said outlets to block the same.

In the construction illustrated by Figs. 80 3 and 4 of the drawings the outlets 39 extend from the tops of the retorts near one end of the long diameter of a retort, and the preheating and feeding tube 27 for a retort terminates substantially at the top of the 85 retort and is located at the opposite end of the long diameter of the retort from the outlet, and as the material fed to the retort will not rise above the angle of repose for the material indicated by the dotted line 41, the 90 material cannot accumulate opposite the outlet of the retort so as to block the same.

The furnace illustrated by Figs. 3 and 4 of the drawings is shown as provided with burners 42 and 43 for gaseous, liquid or pulverized fuel and it will be understood, of course, that the burners 2, 3, 42 and 43 are illustrated conventionally, and any suitable or preferred form of burner for burning liquid or gaseous or pulverized solid fuel, 100 or any mixture of these fuels, may be used as desired. It is preferred to use a gaseous, liquid or pulverized solid fuel, or some mixture of these fuels, as distinguished from ordinary solid fuel, on account of the better 105 regulation of the heat which can be obtained.

The furnace illustrated by Figs. 3 and 4 of the drawings is provided with removable closures 44, for the same purpose as in the 110 furnace illustrated by Figs. 1 and 2 of the drawings, and the base members 38 are supported upon a supporting frame 45 to the interior of which access may be had through doors 46 for the removal of the spent material which has collected in the bottom of the furnace and in the base members 38.

The apparatus is used as follows: The base members, retorts, preheating and feeding tubes and hoppers are filled with the 120 proper charge mixture for effecting the reduction of the material to be reduced in the retorts, for example, the charge may consist of a mixture of zinc oxid and carbonaceous material suitable for reduction, and the retorts are heated by the fuel burning in the combustion chamber of the furnace and supplied thereto by the burners. When the temperature of the retorts has been raised sufficiently, reduction of the zinc oxid will 130

take place within the retorts, the zinc vapor will ascend to the upper parts of the retorts into the pockets adjacent the outlets, and will escape through the outlets to the condensers 5 where the vapor will condense to metallic zinc. The material in the base members effectually seals the interiors of the retorts from the atmosphere, and the material in the preheating and feeding tubes will prevent the escape of any zinc vapor through 10 the feed hoppers.

In both constructions of furnaces illustrated by the drawings the preheating and feeding tubes are exposed to the hot products 15 of combustion, so that the material therein becomes heated sufficiently to drive off the moisture and volatile matters contained therein, but the temperature of the preheating and feeding tubes is not raised 20 high enough to bring about the reduction of the zinc oxid contained therein and the distillation of the zinc vapor. This is due to the fact that in the construction of furnace illustrated by Figs. 1 and 2 of the 25 drawings, the preheating and feeding tubes pass through the roof of the furnace and consequently their entire lengths are not exposed to the hot products of combustion within the furnace, and in the form of furnace illustrated by Figs. 3 and 4 of the 30 drawings, the preheating and feeding tubes not only pass through the roof of the furnace, but are separated from the active combustion chamber of the furnace by the partition 35 25.

As the zinc oxid in a retort is reduced and the carbonaceous material is consumed, the spent material in the retort diminishes or decreases in volume and settles down in 40 the retort, and fresh dried and heated material flows into the retort from the preheating and feeding tube. The material is removed from the base members by the rotation of the revoluble cones 13 in the construction illustrated by Figs. 1 and 2 of the 45 drawings, and this material falls on the conveyer 17 and is removed to the exterior of the furnace.

In the construction illustrated by Figs. 50 3 and 4 of the drawings, the material is removed by the use of hoes or shovels through the doorways provided with the doors 46, and with either form of construction, as the material is removed from the base members 55 the material in the retorts sinks down and fresh material flows into the retorts from the preheating and feeding tubes to maintain the retorts substantially full of material. The retorts are subjected to the most 60 intense heat in the zone in line with the burner nozzles, so that the reduction of the zinc oxid in the retorts is a gradual one as the material in the retorts sinks from the tops of the retorts down to the plane of the 65 burner nozzles and the material cools as it

sinks below the plane of the burner nozzles, so that the spent material by the time it reaches the bottoms of the base members is not highly heated. This method of gradually increasing the temperature of the material to first drive off the moisture and volatile matters and then gradually increasing the temperature to a point sufficient to reduce and volatilize the last remnant of the zinc contained in the charge, effects a gradual and continuous distillation of the zinc vapor without any violent or explosive reaction taking place as would happen were the fresh charge to be subjected to the highest temperature of the furnace immediately 70 upon introduction into the retorts. Any lead, antimony and copper oxid contained in the charge will be reduced to a metallic form and will be removed from the base members with the carbonaceous residue or 75 spent material, and can be separated from the spent material and recovered.

The feeding tubes should have enough of their lengths outside the combustion chamber to condense zinc vapor which may 80 ascend into the material contained therein and may be closed by plugs or valves, if desired.

In the form of furnace illustrated by Figs. 3 and 4 of the drawings, a partition 47 extends longitudinally through the chamber 26 between the two rows of feeding and preheating tubes 27 to prevent short circuiting of the hot products of combustion to the stacks without heating the feeding and 95 preheating tubes 27. The hot products of combustion passing through the aperture 33 into the chamber 26 must pass to stack 30 through the flue exit 36 and the hot products of combustion which pass through the 100 aperture 34 into the chamber 26 pass to stack 29 through the flue aperture 35.

What is claimed is:

1. The combination with a retort and a condenser and an outlet leading from said retort to said condenser, of a preheating and feeding tube for supplying material to said retort so connected to the retort as to maintain a pocket free from material adjacent the outlet to the condenser when the 110 retort has been filled with material through the preheating and feeding tube.

2. The combination with a base member, adapted to retain reduced materials therein and open at its top, of an open bottom retort 115 supported on said base member and provided with a preheating feed pipe extending upward therefrom, and a condenser communicating with the interior of the retort through an outlet in the retort located 120 in the retort above material in the retort when the retort is filled with material through the preheating feed pipe.

3. The combination with a retort open at 125 the bottom and provided with a condenser 130

and a preheating and feeding tube connected to the upper end of the retort, of a base member open at its bottom, for supporting the retort, and a shaft extending up into the base member and provided with an agitator for breaking up crusts or adhering material which may form beneath the reducing zone of the retort.

4. The combination with a furnace provided with a combustion chamber and a partition forming the bottom of the combustion chamber, of retorts open at their bottoms, located in the combustion chamber, base members for said retorts located below said partition, and means for producing a zone of high temperature within said

combustion chamber adjacent the lower ends of said retorts.

5. The combination with a furnace provided with a combustion chamber, of retorts located in said combustion chamber and preheating and feeding tubes extending through the roof of said furnace and communicating with the interiors of said retorts, and means for regulating the heating of said preheating and feeding tubes.

In witness whereof I hereto affix my signature in presence of two witnesses.

EDWARD FINK.
